GUY MOUNTING

Herbert E. Miller, Allentown, Pa., assignor to
 Utilities Service Company, Inc., Allentown, Pa.,
 a corporation of Pennsylvania

Application January 28, 1932, Serial No. 589,489

15 Claims. (Cl. 189—31.5)

This invention relates to guy wire mountings, and more particularly to guy guards.

In my copending applications Serial Nos. 504,-
 920, filed December 26, 1930, and 519,187, filed
 5 February 28th, 1931, there are disclosed and
 claimed novel guy guard constructions which
 are improvements over the prior art in that they
 eliminate the disadvantages of earlier construc-
 tions. For example, it was the common practice
 10 for a number of years to secure guy guards over
 or around guy wires by the use of U-bolts and
 similar fastening devices, and such guards were
 disadvantageous particularly because of the labor
 involved in placing them in position and because
 15 of the relatively expensive fastening means em-
 ployed.

In my copending applications referred to the
 guard constructions are of such character as to
 eliminate the use of separate fastening means by
 20 utilizing one of the usual clamp bolts for secur-
 ing the lower end of the guard, and by provid-
 ing means carried by the guard for engaging the
 guy wire to secure the guard thereto. Such a
 construction possessed the material advanta-
 25 ges over the prior art that it was cheaper to man-
 ufacture and much easier to install, thus sub-
 stantially reducing the total cost of manufac-
 turing and installing the device.

In my copending application Serial No. 580,976,
 30 filed December 14, 1931, I have disclosed a fur-
 ther improvement in the art of guy wire mount-
 ings. It has been the common practice to secure
 the lower ends of guy wires to anchoring means
 therefor by providing ground anchors having
 35 shanks terminating at their upper ends in eyes,
 and the lower ends of the guy wires are looped
 around thimbles connected to the eyes. Such
 a construction is disadvantageous for the reasons
 disclosed in my copending application Serial No.
 40 580,976. Such disadvantages reside in the ne-
 cessity of having to cut off the guy cable to ap-
 proximate lengths with the attendant difficulty
 of completing the operations of threading the guy
 wire through the thimble, drawing it taut and
 45 securing it to the clamping bolt. After such
 operations are completed the end of the length
 of guy cable is cut off adjacent the clamp and
 left lying in the vicinity of the guy guard. My
 copending application last referred to overcomes
 50 these several difficulties by eliminating the ne-
 cessity of cutting the guy cable until after com-
 plete installation has been made, thus eliminating
 the leaving of a short piece of cable on the adja-
 cent ground. The construction referred to also
 55 greatly facilitates the guy cable installation

whereby it will be apparent that labor costs due
 to installation are materially reduced.

An important object of the present invention
 is to provide a greatly improved guy wire in-
 stallation, and particularly with reference to the
 guy guard, wherein more efficient anchoring
 means for the guard is provided without the
 necessity of installing it by first hooking the up-
 10 per engaging means around the wire with the
 guard extending at an angle to the wire, and then
 swinging the guard downwardly to operative posi-
 tion.

More specifically, an important object of the
 present invention is to provide a guard construc-
 15 tion of such character as to permit the guard
 to be placed in position by moving it into engage-
 ment therewith from a position parallel thereto,
 and wherein the securing of the guard in position
 is accomplished so quickly and easily that the
 20 labor costs of installation are greatly reduced.

A further object is to provide a guy guard which
 may be quickly and readily secured in position
 with respect to the guy strand without even the
 necessity of removing the nut of one of the clamp
 25 bolts.

A further object is to provide a guard of the
 character referred to which may be secured in
 position solely by the use of a simple tool such
 as a bolt, a handle of a pair of pliers, etc.

A further object is to provide a novel guard 30
 which is operative, when secured to the guy
 strand, for taking up any slack which may be
 present in the latter.

A further object is to provide novel anchoring
 means for the guy strand which is adapted to co- 35
 operate with the guy guard for securing the lower
 end of the latter in operative position.

A further object is to provide an anchor rod
 construction which possesses all of the advan-
 tages of the structure shown in my copending 40
 application Serial No. 580,976, previously re-
 ferred to, together with the additional advantage
 that it is operative for securing the lower end
 of the guy guard in operative position.

Other objects and advantages of the invention 45
 will become apparent during the course of the
 following description.

In the drawings I have shown several embodi-
 ments of the invention. In this showing,

Figure 1 is a face view showing the device in- 50
 stalled.

Figure 2 is an enlarged central longitudinal
 sectional view, parts being broken away,

Figure 3 is a transverse section on line 3—3 of
 Figure 2,

Figure 4 is a similar view on line 4—4 of Figure 2.

Figure 5 is an upper end view of the guy guard.

Figure 6 is a face view similar to Figure 1 showing 5 a modified form of the device.

Figure 7 is a longitudinal sectional view of a further modified form of the device, parts being shown in elevation.

Figure 8 is a similar view of the same taken at 10 right angles to Figure 7, parts being shown in elevation.

Figure 9 is a transverse sectional view on line 9—9 of Figure 7.

Figure 10 is a similar view on line 10—10 of 15 Figure 7, and,

Figure 11 is a view similar to Figure 10 showing 20 a somewhat modified form of guard anchoring means.

Referring to Figures 1 to 5 inclusive, the 25 numeral 10 designates an ordinary guy strand such as those used in connection with telephone and telegraph poles and the like. The guy cable is shown as having its lower end passing around a thimble 11, and the opposite strands of the cable 25 are secured together by bolts 13 beneath the nuts of which are arranged washers 14. The thimble 11 passes through the eye 15 carried by the upper end of an anchor rod 16.

The guy guard is indicated as a whole by the 30 numeral 17 and is preferably formed of sheet metal. The body of the guard is arcuate in cross section and may be any desired portion of a complete circle, and preferably is at least semi-circular. In Figures 3 and 4, the guard is shown 35 in cross-section as extending throughout approximately 270°, in which case the opening 18 defined between the edges of the body of the guard is sufficiently wide to permit the entrance of the clamp 12 therebetween. If desired, the body of 40 the guard may be substantially a complete circle, in which case the portion of the edges of the guard lying adjacent the clamp 12 will be cut away to permit the entrance of the clamp thereinto.

The upper end of the guard is preferably provided 45 with any suitable means for engaging the wire without clamping or engaging against opposite sides thereof. In Figures 2 and 5, the body of the guard is shown as being provided with 50 a sheet metal cap 19 having a radial slot 20 formed therein with a semi-circular inner end 21 lying substantially axially with respect to the guard and through which the guy wire is adapted to extend. The portion of the cap 19 defining the slot 20 is preferably turned downwardly as 55 at 22 to form a flange of substantial width to engage against the wire, as shown in Figure 2, to prevent the raw edge of the metal from scraping the wire and abrading the galvanizing thereon. Outwardly of the slot 20, the cap is preferably provided with outwardly diverging edges 23 to facilitate the movement of the cap to operative position with respect to the guy wire.

In my copending application Serial No. 519,187, 60 previously referred to, I have disclosed means for securing the lower portion of the guard to one of the bolts of the clamp. With the present invention, it has been found unnecessary to remove any of the nuts from the clamp, since the device 65 may be anchored in position without actually being positively secured by one of the clamp bolts. Referring to Figures 1, 2 and 3, it will be noted that the guard is provided with a plurality of depressions 23 preferably diametrically opposite the split 70 75 in the guard. Each of these depressions is pro-

vided with an opening 24 substantially centrally thereof and defined by an inwardly stamped flange 25. The opening 24 in each depression may be of any desired shape, depending upon the element which it is to receive, and is shown in the present instance as being circular to receive one of the washers 14.

A plurality of the depressions 23 is provided merely for the purpose of adjustment whereby the lower end of the guard may be arranged at any desired height from the ground depending upon which of the openings 24 is utilized for anchoring the lower end of the guard, and upon which of the washers 14 the opening surrounds. In Figure 2, the lowermost opening 24 and its flange 25 is shown as surrounding the uppermost washer 14, and it will be apparent that when the device is in position, the inner edge of the flange 25 contacts against the outer face of the adjacent element of the clamp 12. When the guard is secured in position by means to be referred to, the seating of the inner edge of the flange 25 against the clamp assists in preventing rotation of the guard with respect to the guy strand.

For the purpose of securing the guard to the 25 strand a plurality of engaging members 26 is provided. For most installations only one of the engaging members 26 is necessary, but it is preferred to employ two of these members in order that any excess slack of the guy strand may be 30 taken up, in a manner to be described. When two of the engaging members are employed, they are preferably placed apart a considerable distance, as shown in Figure 1. The engaging members 26 are identical in construction and 35 only one need be described in detail. It will become apparent, however, that the engaging elements are reversed with respect to each other and are arranged on opposite sides of the center 40 of the guard as defined by a plane passing through the axis of the body intermediate the edges of the opening 18.

Referring to Figure 3 it will be noted that one side of each of the engaging members 26 is curved 45 to conform to the curvature of the inner surface of the guard and lies thereagainst. Such curved edge of the engaging member is provided with an outstanding lug 27 extending through a suitable opening in the body of the guard, and after the engaging member has been placed in position, a 50 suitable welding device is placed against the outer face of the lug 27 to weld it securely to the body of the guard. Substantially opposite the curved face referred to, each engaging element is provided with a slightly inclined face 28 beyond 55 the outer end of which is arranged a notch 29 in which the guy strand 10 is arranged when the device is locked in position. Adjacent each member 26, and substantially diametrically opposite the opening 18, the body of the guard is provided with an opening 30 for the reception of a suitable tool 31 for moving the guy strand into either notch 29. In the present instance, the tool 31 is shown as an ordinary bolt such as usually is carried by a lineman, but it will be apparent that a screw driver, the handle of a pair of pliers, or any other suitable implement may be employed.

In some instances, it is desired to have the guy 70 guard extend downwardly to the surface of the ground, in which case it is unnecessary to support the guard against downward movement. The form of the invention shown in Figure 6 is adapted for such use. As shown, the body of the guard may be of uniform cross sectional shape 75

throughout its length without the provision of the depressions 23. The engaging members 26 are employed as in the previous case, and each end of the guard is provided with a cap 32 which may be identical with the cap 19 previously described, and need not be referred to in detail. It will be apparent that these caps will prevent movement of the guard laterally with respect to the guy strand in every direction except radially in alignment with the slots provided in the caps 32. The engaging members 26, however, prevent such movement of the guy guard unless it is deliberately released in a manner to be described.

In the form of the invention shown in Figures 7 and 8, means are provided for securing the lower end of the guard to the anchor rod rather than to the guy clamp. In such modified form, the invention may employ a guy guard which is identical with the form of the guard illustrated in Figures 1 to 5 inclusive except for the particular formation of the depressions in the guard, and accordingly the guard need not be referred to in detail. For convenience, the parts of the guard which are identical with the form shown in Figures 1 to 5 inclusive are illustrated by the same reference numerals. In place of the depressions 23, the guard may be provided with one or more similar depressions 33. Instead of being provided with relatively large openings 24 surrounded by the flanges 25, however, the base of the depression 33 is provided with an opening 34 for a purpose to be described.

The form of the invention shown in Figures 7 to 10 inclusive, employs an anchor rod 35 the shank and base of which may be conventional and accordingly need not be referred to in detail. The upper end of the anchor rod is provided with a head indicated as a whole by the numeral 36. This head is provided on opposite sides with flanges 37 connected at the bottom of the head, and these flanges slope or are curved downwardly and outwardly as shown in Figure 7 to form a saddle having a groove 38 at the lower portion around which the guy strand 16 passes.

The upper end of the head 36 terminates in a plane at right angles to the axis of the guard as indicated by the numeral 39. Adjacent its upper end, the head 36 is provided with opposite inturned flanges 40 within which opposite strands 50 of the guy wire are adapted to be arranged. The usual guy clamp 12 is provided, and when in operative position, the clamp has its lower end seated against the upper end of the head 36. The free end of the guy strand is cut off after installation is completed, adjacent the upper end of the clamp 12 as indicated at 42.

The head 36 is extended to form a flat boss 43, as shown in Figures 7 and 10, and an opening 44 is drilled and tapped through the head 36 substantially centrally of this boss. A machine or similar screw 45 is inserted through the opening 34 of the guard and into the opening 44 for securing the lower end of the guard in position.

In Figure 11 of the drawings a slightly modified form of anchoring means is illustrated for securing the lower end of the guard to the head 36. The screw 45 provides means for positively securing the guard to the anchor rod, whereas the form illustrated in Figure 11 provides means which is fully operative in conjunction with the engaging members 26 for preventing displacement of the guard from the guy strand without the use of separate fastening elements. Referring to Figure 11, it will be noted that a boss 46 is provided which is quite similar to the boss

43 except that it is not drilled and tapped to provide a screw receiving opening, but is provided with a smaller outstanding boss 47 or any desired shape. This form of the invention is adapted for use in connection with a guard identical with that illustrated in Figures 1 to 5 inclusive, in which case one of the flanges 25 is adapted to surround the small boss 47 with its inner edge contacting with the outer face of the larger boss 46.

The operation of the device is as follows:

In the form of the invention shown in Figures 1 to 5 inclusive, the opening 18 may be wide enough to permit the guard to be slipped over the clamp 12, or the body of the guard may be substantially circular with a cut away portion adjacent the lower end of the guard of a width approximating the width of the opening 18 for the same purpose. Moreover it will be apparent that the guard may be semi-circular or of any other desired shape. When it is desired to place the guard in position, it may be arranged parallel to the guy strand and then moved laterally directly to operative position with the guy strand arranged in the slot 20 of the cap 19. There will be no gripping action whatever against the guy strand at such time, and accordingly the body of the guard may be freely moved longitudinally of the guy strand to its desired position as to height with one of the openings 24 in alignment with one of the washers 14. Such washer obviously is receivable in the opening 24 referred to, whereupon the guard will be fixed against longitudinal movement with respect to the guy strand. In this connection, it will be apparent that the washer 14 forms a convenient element for reception within one of the openings 24, but the use of the guard is not limited to the use of the washers themselves as means for fixing the guard against longitudinal movement. For example, the opening may be shaped to receive the end of one of the bolts projecting beyond the nut, or it may be shaped to receive one of the nuts themselves. Moreover, either of the clamping elements may be provided with a projecting portion with the openings 24 shaped to selectively receive such projection. In other words, one of the elements of the clamp may be provided with a lug such as the lug 47 illustrated in Figure 11.

After the guard has been placed in operative position with the guy strand arranged in the slot 20 and one of the washers 14 arranged in one of the openings 24, the guy strand will have a portion within the body 17 lying in the small depression at the inner end of the face 28 of each engaging member 26. The operator then inserts any suitable implement through one of the openings 30, as indicated in solid lines in Figure 3. For this purpose, any convenient implement may be employed, such as a fairly long bolt, a screw driver, a handle of a pair of pliers, etc. The implement is moved in the direction of the arrow in Figure 3 to the dotted line position and beyond such position, and during such movement, the implement contacts with one side of the opening 30 as a fulcrum and forces the adjacent portion of the guy strand along the inclined face 28, and thence into the notch 29. The tension of the guy strand under ordinary conditions will effectively maintain the strand in the notch 29 against manual displacement. In other words, if the guy strand is under normal tension, such tension is sufficient to prevent accidental or malicious removal of the guard by direct pressure exerted laterally thereagainst.

Occasionally, after a guy strand has been in use for a considerable period of time, it becomes less taut, for various reasons, and the present device operates to restore the guy strand to its normal degree of tautness and at the same time causes the guy strand to securely anchor the device in position. Where the guy strand is normally taut it is necessary to employ only one of the engaging members 26, but when the wire has become slack, both members 26 are preferably employed. As will be apparent from Figures 1 and 3, the notches 29 of the two members 26 are arranged on opposite sides of a plane passing through the axis of the body 17 and through the opening 18 centrally thereof. Accordingly the guy strand will be forced in one direction to engage one notch 29 and in the opposite direction to engage the notch of the other member 26, thus providing oppositely facing wire engaging means, and causing the guy strand to follow a sufficiently zigzag path to take up the slackness and restore the guy strand to a normal taut condition. The guy strand may be released from either nut 29 by inserting a suitable implement through the opening 18 in engagement with one side thereof, and then prying the guy strand out of the notch. Such action requires a substantial degree of leverage for its performance and cannot be accomplished by the direct application of manual force.

The form of the invention shown in Figure 6 is identical with the form previously described so far as the engaging members 26 are concerned. The modified form is applicable in installations where it is desired to have the guy guard extend into contact with the ground. Under such conditions, the two end caps 32 serve to center the guy strand with respect to the body 17, while the members 26 serve to secure the guard to the guy strand. The guard merely is permitted to slip downwardly into contact with the ground prior to the action of engaging the guy strand within the notches of the members 26.

The form of the invention shown in Figure 6 to 10 inclusive also is installed in the same manner as in the previous cases so far as the members 26 are concerned, the screw 45 being applied prior to the operation of engaging the guy strand within the notches of the members 26. In this case, the screw 45 serves as positive means for securing the guard in position, but does not require the removal of one of the nuts of the clamp bolts. In this form of the invention, the clamp 41 seats against the upper end of the head 36, and if the guy strand becomes somewhat slack, it prevents downward movement of the clamp and the lower portion of the guy strand, and thus prevents the latter from becoming disengaged from the groove 38. This action is disclosed in my pending application Serial No. 580,976 referred to above, but is of less importance in the present case since the engagement of the guard against the lug 43 operates to prevent disengagement of the loop of the guy strand from the groove 38.

The operation of the modified form shown in Figure 11 is identical with that previously described except that there is no positive securing of the guard in position, the flange 25 being placed in position around the small lug 47 prior to the operation of engaging the guy strand within the notches of one or more of the members 26. In connection with this form of the invention, attention is invited to the fact that there is no eye or similar device such as the thimble 11 through which the guy wire is to be threaded and which would necessitate the cutting off of the

wire as is the present practice. The operator merely places the guy strand within one of the hooks 40, and then bends the wire around the groove 38 and engages the end of the wire within the other hook 40. Such operation places opposite strands of the wire substantially in the proper position to be clamped between the elements of the clamp 41, after which the guy strand is cut off as at 42 from the reel of wire, thus eliminating the discarding of a short section of wire, as is usually the case.

From the foregoing it will be apparent that the present device permits the placing of the guard in approximately normal position directly from one side of the guy strand and from a position parallel thereto. This action eliminates the necessity of swinging the lower end of the guard through an arm of approximately 90 per cent. as in the case of the structure shown in my co-pending application Serial No. 519,187. In some installations this swinging of the guard is permitted to take place only with difficulty. Moreover, after the guard has been placed approximately in operative position in accordance with the present invention, the guard may be freely moved longitudinally or revolved as may be necessary to properly align one of the flanges 25 on the opening 34 with the element which it is to receive. Thus any abrading of the wire and consequent injury to the galvanizing thereon while moving the guard to operative position is eliminated. The forms of the invention shown in Figures 1 to 6 inclusive and 11 are adapted to be placed in position without the use of fastening elements as such.

From the foregoing it will be apparent that the operation of the engaging members 26 is not specifically dependent upon the particular means for centering the guard with respect to the guy wire and for preventing longitudinal movement of the guard. In other words, the engaging means 26 is operative if the guard is fixed against longitudinal movement with respect to the clamp, as shown in Figure 2, or with respect to the anchor rod, as shown in Figure 7. Moreover, the engaging means 26 is operative in the manner shown in Figure 6 with a portion of the upper end of the guard contacting with the guy wire and a portion of the lower end contacting with the shank 16 of the anchor rod. In a number of the claims therefore, the guard has been defined as being mounted with respect to the "guy wire structure" which term is intended to include all of the elements of the structure, not including the guard, such as the guy wire, clamp and anchor. Moreover, the manner of mounting the guard with respect to the clamp is not limited to the use of one of the washers 14, as in the specific embodiment shown in Figure 2, but may be mounted with respect to one of the nuts, to a projection carried on one of the clamp elements, etc. Any definitions in the following claims therefore, which call for the mounting of the guard with respect to the clamp, are intended to cover any portions of the clamp including the nuts or bolts thereof.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. A device of the character described com- 75

- prising an elongated guard of sheet material adapted to at least partially surround a guy wire structure, means carried by said guard adjacent opposite ends thereof and adapted to contact with the guy wire structure, and an engaging device carried by said guard intermediate its ends and provided with a notch lying to one side of the normal line of the guy wire and facing away from such normal line, said engaging device being further provided with an inclined face extending from the normal line of the guy wire to said notch and along which the guy wire is adapted to be moved from its normal position into position in engagement with said notch.
2. A device of the character described comprising an elongated guard of sheet material adapted to at least partially surround a guy wire structure, means carried by the guard adjacent its upper end and including a radially opening notch adapted to receive the guy wire, the lower end of the guard having a portion engageable against a portion of the guy wire structure, means for securing said portion of the guard to the guy wire structure, and an engaging device carried by said guard intermediate its ends and provided with a portion lying to one side of the radial plane of said notch and adapted to be engaged by the guy wire upon the lateral offsetting thereof into engaging position with respect thereto.
3. A device of the character described comprising an elongated guard of sheet material adapted to at least partially surround a guy wire structure, means carried by the guard adjacent its upper end and including a radially opening slot adapted to receive the guy wire, means adjacent the lower end of the guard for engaging against a portion of the guy wire structure, means for securing said last named means to the guy wire structure, and an engaging device carried by said guard intermediate its ends and provided with a notch lying to one side of the radial plane of said slot and facing away from the normal line of the guy wire, said notch being adapted to receive the guy wire upon the lateral offsetting thereof into engaging position with respect to said notch.
4. A device constructed in accordance with claim 3 wherein said engaging device is provided with an inclined face extending from the normal line of the guy wire to said notch to guide the guy wire for movement thereinto.
5. A device of the character described comprising a guard adapted to at least partially surround a guy wire structure, a cap carried by the guard adjacent its upper end and including a radially opening slot adapted to receive the guy wire, the lower end of the guard being provided with means facing in the same direction as said slot and adapted to engage against a portion of the guy wire clamp and to receive a portion thereof to prevent longitudinal movement of the guard, and an engaging device carried by said guard intermediate its ends and provided with a portion lying to one side of the radial plane of said slot and adapted to be engaged by the guy wire upon the lateral offsetting thereof into engaging position with respect thereto.
6. A device of the character described comprising a guard adapted to at least partially surround a guy wire structure, a cap carried by the guard adjacent its upper end and including a radially opening slot adapted to receive the guy wire, the lower end of the guard being provided with means facing in the same direction as said slot and adapted to engage against a portion of the guy
- wire clamp and to receive a portion thereof to prevent longitudinal movement of the guard, and an engaging device carried by said guard intermediate its ends and provided with a notch lying to one side of the radial plane of said slot and facing away from the normal line of the guy wire, said device being further provided with an inclined face extending from the normal line of the guy wire to said notch to guide the guy wire for movement thereinto.
7. A device of the character described comprising a guard having a longitudinal opening extending throughout its length, a cap carried by the upper end of the guard and provided with a radial slot extending to and communicating with said longitudinal openings, said guard being provided adjacent its lower end at a point diametrically opposite said longitudinal opening with an inwardly extending flange adapted to receive a portion of the guy wire clamp and to contact with said clamp to prevent longitudinal movement of the guard, and an engaging member having a notch laterally offset from the radial plane of said slot to be engaged by the guy wire upon the lateral offsetting thereof into engaging position with respect to said notch.
8. A device of the character described comprising a guard having a longitudinal opening extending throughout its length, a cap carried by the upper end of the guard and provided with a radial slot extending to and communicating with said longitudinal opening, said guard being provided adjacent its lower end at a point diametrically opposite said longitudinal opening with an opening defined by an inwardly extending flange and corresponding in shape to and receiving a portion of the guy wire clamp with the inner edge of the flange contacting with the clamp to prevent longitudinal movement of the guard, and an engaging device carried by said guard intermediate its ends and provided with a notch lying to one side of the radial plane of said slot and facing away from the normal line of a guy wire, said notch being adapted to receive the guy wire upon the lateral offsetting thereof into engaging position with the notch, said engaging device having an inclined face leading to the notch to facilitate movement of the guy wire thereinto.
9. A device of the character described comprising a guard adapted to at least partially surround a guy wire structure, means carried by said guard adjacent opposite ends thereof and adapted to contact with the guy wire structure, and an engaging device carried by said guard intermediate its ends and provided with a notch lying to one side and facing away from the normal line of the guy wire, said notch being adapted to receive the guy wire upon the lateral offsetting thereof into engaging position with respect to said notch, said guard being provided adjacent said engaging device with an opening adapted for the insertion of a tool operable for effecting lateral offsetting of the guy wire.
10. A device of the character described comprising a guard having a longitudinal opening extending throughout its length, a cap carried by the upper end of the guard and provided with a radial slot extending to and communicating with said longitudinal opening, said guard being provided adjacent its lower end at a point diametrically opposite said longitudinal opening with means engageable with the guy wire structure to prevent longitudinal movement of the guard with respect thereto, and an engaging member having a notch laterally offset from the radial plane of said slot

- to be engaged by the guy wire upon the lateral offsetting thereof into engaging position with respect to said notch, said guard being provided with an opening adjacent said engaging member and substantially diametrically opposite said longitudinal opening for the reception of an implement operable for effecting the lateral offsetting of the guy wire into engaging position with said notch.
11. A device of the character described comprising a guy wire anchor rod having a saddle around which the guy wire is adapted to pass, a guard at least partially surrounding the guy wire and engaging the latter at the upper end of the guard, said saddle having a projection engaging a portion of the guard to prevent longitudinal movement thereof, and engaging means carried by the guard intermediate its ends and provided with a notch laterally offset from and facing away from the normal line of the guy wire, said engaging means being further provided with an inclined face along which the guy wire is adapted to be moved laterally from its normal position for reception in said notch.
12. A device of the character described comprising a guy wire anchor rod having a saddle around which the guy wire is adapted to pass, a clamp for the guy wire arranged above the anchor rod, a guard at least partially surrounding the guy wire and engaging the latter at the upper end of the guard, said saddle having a flat extended face lying in a plane substantially parallel to the axis of the guard and a lug projecting outwardly from said face, said guard being provided near its lower end with an opening corresponding in shape and size to and receiving said lug with the portions of the guard adjacent said opening contacting with said face, and engaging means carried by the guard intermediate its ends and provided with a notch laterally offset from and facing away from the normal line of the guy wire to be engaged by the guy wire upon the lateral offsetting thereof into engaging position with respect to said notch.
13. An anchor rod for guy wire structures comprising an elongated body having a head formed at its upper end, said head having its lower portion offset from the body to form a saddle provided with a groove around which the guy wire is adapted to pass, said saddle being provided outwardly of the groove with a substantially flat face arranged in a plane parallel to said body, said saddle being further provided with a lug extending outwardly from said face for reception within an opening formed in a guy guard
14. A device of the character described comprising an anchor rod, a guy wire, and an elongated guard of sheet metal adapted to at least partially surround the guy wire, said anchor rod having an integral offset head provided with an open groove forming a saddle around which the guy wire is adapted to pass to be secured with respect to said anchor rod, said head having an outer face portion engaging against a correspondingly shaped inner face portion of the guy guard and secured thereto.
15. A device of the character described comprising an anchor rod, a guy wire, an elongated guard of sheet metal adapted to at least partially surround the guy wire, said anchor rod having an integral offset head provided with an open groove forming a saddle around which the guy wire is adapted to pass to be secured with respect to said anchor rod, said head having an outer face of substantial area engageable against a similarly shaped inner face portion of the guy guard, and means for securing said guy guard to said head.
